CLAIM

The ornamental design for a dispensing cap, as shown and described.

DESCRIPTION

FIG. 1 is a top front perspective view of a dispensing cap in a closed position;

FIG. 2 is a top rear perspective view in an open position;

FIG. 3 is a right side elevation view in a closed position, the left side elevation view being a mirror image thereof;

FIG. 4 is a left side elevation view in an open position, the right side elevation view being a mirror image thereof;

FIG. 5 is a front elevation view in a closed position;

FIG. 6 is a top plan view in a closed position;

FIG. 7 is a top plan view in an open position;

FIG. 8 is a bottom view in a closed position; and,

FIG. 9 is a rear elevation view.

The broken lines in the drawings are for illustrative purposes only and form no part of the claimed design.
